C. L. WEISS

CAN OPENER

Filed Sept. 6, 1923

Inventor.
C. L. Weiss
Attala J. Evans
attorney.

UNITED STATES PATENT OFFICE.

CHARLES L. WEISS, OF SANTA MONICA, CALIFORNIA.

CAN OPENER.

Application filed September 6, 1923. Serial No. 661,248.

To all whom it may concern:

Be it known that I, CHARLES L. WEISS, a citizen of the United States, residing at Santa Monica, in the county of Los Angeles and State of California, have invented new and useful Improvements in Can Openers, of which the following is a specification.

This invention relates to improvements in can openers and has particular reference to 10 an economically constructed adjustable can opener, which may be readily operated without undue effort on the part of the user.

Another object is to produce a device of this character which is extremely cheap and 15 therefore well within the purchase price of the average user.

A still further object is to produce a can opener which will occupy a limited amount of space when not in use.

20 Another object is to produce a can opener which will eliminate the usual danger incident to the using of a cutter which is rotated around the can.

Other objects and advantages will be apparent during the course of the following description.

In the accompanying drawings forming a part of this specification, and in which like numerals are employed to designate like 30 parts throughout the same.

Figure 1 is a perspective view of my can opener,

Figure 2 is a side elevation of Figure 1, and

35 Figure 3 is a cross section taken on the line 3—3 of Figure 2.

Applicant is aware of the fact that many can openers have been devised, which can openers, in most instances, were rotated 40 around the edge of the can with a rocking motion. It often occurred that these types of can openers slipped and caused serious personal injury.

I have therefore perfected a can opener, 45 which may be actuated up and down thereby cutting the top without any danger to the operator.

In the accompanying drawings wherein for the purpose of illustration is shown a 50 preferred embodiment of my invention, the numeral 5 designates a base member which

is preferably formed of a blank having turned edges as shown at 7.

An upstanding portion 9 is formed at right angles to the base and may be made integral with the base 5.

A slider 12 is positioned upon the upstanding portion 9 and has secured thereto a curved cutter 13. This slider has an offset portion 14 within which are formed recesses 60 as shown at 16. These recesses are adapted to engage the arms 17 and 18 of a U-shaped handle 19. The ends of these legs are in turn adapted to extend through holes 21 formed in the upstanding portion. 65

The method of operating my can opener is as follows:—

Assuming that the parts are arranged as shown in Figure 1, the can is placed upon the base 5 and the handle 19 is grasped and the downward movement of the handle 19 causes the cutter 13 to puncture the top of the can. The handle is then moved upwardly and the can turned a short distance, after which the handle is again forced down. 75 In this manner the cut is extended until the entire top has been cut from the can.

It will thus be seen that this method eliminates all danger incident to the opening of a can.

80 It is to be understood that the form of my invention herewith shown and described is to be taken as a preferred example of the same, and that various changes in the shape, size and arrangement of parts may be resorted to without departing from the spirit of the invention or the scope of the subjoined claim.

Having thus described my invention, I claim:—

90 In a can opener, a base, an upstanding portion, a slider movable on said upstanding portion, a cutting element mounted on said slider, means for imparting a reciprocatory movement to said slider, said means comprising a U-shaped handle extending through the offset portion of said slider and adapted to have its ends received in suitable openings in said upstanding portion.

95 In testimony whereof I affix my signature.

CHARLES L. WEISS.
